DESIGN FOR A FISH BAIT

Fred E. Nichols, Corpus Christi, Tex.

Application May 16, 1940, Serial No. 92,415

Term of patent 7 years

To all whom it may concern:

Be it known that I, Fred E. Nichols, a citizen of the United States, residing at Corpus Christi, county of Nueces, and State of Texas, have invented a new, original, and ornamental Design for a Fish Bait, of which the following is a specification, reference being had to the accompanying drawing, forming a part thereof, in which:

Figure 1 is a side elevational view of a fish bait showing my new design; Fig. 2, a top plan view; Fig. 3, a front end view; and Fig. 4, a rear end view thereof.

I claim:

The ornamental design for a fish bait, as shown.

FRED E. NICHOLS.
